(Cl. D83—1)

To all whom it may concern:

Be it known that I, Serge Heftler-Louiche, a citizen of France, residing at Paris, France, have invented a new, original, and ornamental Design for a Combined Atomizer and Container, of which the following is a specification, reference being had to the accompanying drawing, forming part thereof.

In the drawing

Fig. 1 is a front perspective view of a combined atomizer and container, showing my new design, the container being shown in open position;

Fig. 2 is a front elevational view of the container in closed position,

Fig. 3 is a side elevational view of the container in closed position, and

Fig. 4 is a top plan view of the container in closed position.

I claim:

The ornamental design for a combined atomizer and container, substantially as shown.

SERGE HEFTLER-LOUCHE.
